US0D1089187S

(12) **United States Design Patent** (10) Patent No.: **US D1,089,187 S**
(45) Date of Patent: ** Aug. 19, 2025

(54) **COMPUTER INTERFACE**

(71) Applicant: **Coda Systems Limited**, Halstead (GB)

(72) Inventors: **Howard Davis**, Halstead (GB); **George Davis**, Halstead (GB)

(**) Term: **15 Years**

(21) Appl. No.: **35/517,321**

(22) Filed: **Mar. 7, 2023**

(80) **Hague Agreement Data**

Int. Filing Date: **Mar. 7, 2023**

Int. Reg. No.: **DM/228988**

Int. Reg. Date: **Mar. 7, 2023**

Int. Reg. Pub. Date: **May 26, 2023**

(51) **LOC (15) Cl.** **14-02**

(52) **U.S. Cl.**

USPC **D14/357**

(57) **CLAIM**

The ornamental design for a computer interface as shown and described.

DESCRIPTION

1. Computer interface
2. Computer interface
3. Computer interface
- 1.1 : Front
- 1.2 : Perspective
- 1.3 : side view
- 1.4 : Back
- 2.1 : Front
- 2.2 : Perspective
- 2.3 : side view
- 2.4 : Back
- 3.1 : Front
- 3.2 : Perspective
- 3.3 : side view
- 3.4 : Back

Design 1 shows a small magnetic computer interface assembly; Design 2 shows a medium magnetic computer interface assembly; Design 3 shows a large magnetic computer interface assembly.

The broken lines in the reproductions depict portions of the computer interface that form no part of the claim.

1 Claim, 12 Drawing Sheets
